UNITED STATES PATENT OFFICE.

HARRY J. HICK, OF ALLIANCE, OHIO, ASSIGNOR TO THE McCASKEY REGISTER COMPANY, OF ALLIANCE, OHIO, A CORPORATION OF OHIO.

FILING APPLIANCE.

1,072,607.

Specification of Letters Patent.

Patented Sept. 2, 1913.

Application filed December 12, 1910. Serial No. 596,902.

To all whom it may concern:

Be it known that I, HARRY J. HICK, a citizen of the United States, residing at Alliance, in the county of Stark and State of 5 Ohio, have invented certain new and useful Improvements in and Relating to Filing Appliances, of which the following is a specification.

This invention relates to a filing appliance 10 adapted for the filing of papers, sales slips, bills, memoranda and the like in classified order.

For the purpose of illustration, I have, in the accompanying drawings, shown and 15 herein described one form of filing appliance embodying my invention.

Figure 1 is a front view of a filing appliance, embodying my invention, the front doors of the casing being shown open. Fig. 20 2 is a side elevation, the near side of the casing being removed. Fig. 3 is a side elevation of the key control mechanism. Fig. 4 is a front view of the parts shown in Fig. 3, a portion of the front plate being broken 25 away and a part of a paper holding case or section, which contains a series of paper holding leaves shown. Fig. 5 is a horizontal section on the line 5—5 of Fig. 3 with one of the lock and release members shown 30 in operative position and a trip device of a bill holding section ready to engage therewith. Fig. 6 is a vertical sectional view on the line 6—6 of Fig. 5. Figs. 7, 8, and 9 are detail views.

35 In the drawings, 1 indicates a casing or cabinet of any preferred or standard construction adapted to house the mechanism or apparatus. The casing 1 comprises side and rear walls 1^a, 1^b, a top 1^c, a bottom or 40 base 1^d, and upper and lower doors 1^e for the front. The casing may be mounted on casters or rollers 1^f, whereby it can be conveniently moved from place to place.

45 2 indicates a frame, preferably U-shaped and inverted, supported in the casing 1.

3 indicates a transverse shaft having its opposite ends suitably journaled in the legs 2^a of the frame 2, preferably near the lower or free ends thereof.

50 3^a, 3^b, indicate a pair of lower spaced chain wheels each keyed to the shaft 3.

3^b, 3^a, indicate a pair of upper spaced chain wheels (only one being shown) each aligned with one of the chain wheels 3^a.

Each wheel 3^b is mounted upon a suitable 55 shaft 3^c supported by the adjacent leg 2^a of the frame 2 near its upper end.

4, 4, indicate a pair of chains each engaging with and running around a lower chain wheel 3^a and an upper chain wheel 3^b. 60

5 indicates a shaft mounted in suitable bearings in one of the legs 2^a and carrying upon its inner end a gear wheel 5 adapted to mesh with the adjacent chain wheel 3^a.

5^b indicates a pulley fixed to the shaft 5 65 on its outer end.

6 indicates a motor, preferably of the electric type, mounted on the bottom 1^c of the casing. The shaft 6^a of the motor is provided with the worm 6^b which meshes 70 with the worm 6^c mounted upon a transverse shaft 6^d.

6^e indicates a pulley fixed to the shaft 6^d.

6^f indicates a suitable belt running over the pulleys 6^e and 5^b, whereby the motor is 75 connected to and drives the latter pulley to rotate the adjacent chain wheel 3^a. As the chain wheels 3^a are fixed to the shaft 3, they will rotate together, and drive the chains in unison. 80

7 indicates a series of paper or bill holding devices or sections each pivotally connected to and supported by the chains 4, 4. The pivotal axis for each bill holding device is arranged at such point above its center of 85 gravity that it will normally hang therefrom vertically and always maintain such position as it swings around the chain wheels from one run of the chains to the other run. The devices 7 are equally spaced from each 90 other along the chains 4 so that those upon one run of the chain substantially counter-balance those upon the other run thereof.

Each device 7 preferably comprises a case 7^a having a base 7^b, side walls 7^c, and a back 95 7^d, and a series of pivotally mounted leaves or frames 7^e. Each device 7 may also include a locking member 7^f for holding the leaves in the case when not in use or during their movement to and from the operative 100 position by the chains 4.

8 indicates a desk or writing board pivotally supported at its rear end by side frames of the casing, whereby it may be folded up into a position behind the doors 105 1^e (see dotted lines in Fig. 2).

8^a indicates a pair of brackets or rods pivotally connected at their upper ends to

the desk 8. The lower or free ends of the rods 8^a fit into recesses 8^b formed in feet 8^c which are supported on a horizontal plate 8^d at the front of the casing. The rods 8^a support the desk in substantially a horizontal position, as shown in Figs. 1 and 2.

The desk 8 is arranged at a convenient height from the floor for writing purposes and for operating the leaves or frames 7^e when 10 a case 7^a containing the latter is moved into a position immediately behind the desk 8 with its base 7^b in substantially the same horizontal plane therewith.

1^f, 1^g, indicate frame members arranged 15 forward of the chains 4 within the casing 1 and rising vertically from the desk 8. They may be connected together at their upper ends by a plate 1^g. These frames are set 20 wide enough apart to permit the operation of the leaves 7^e, but hide from view the chains 4 and other parts of the mechanism. The frame members 1^f, plate 1^g and desk 8 define an opening relative to which each of 25 the bill holding devices are moved for purposes of manipulation. When one of the devices or sections 7 is in such position, the leaves 7^e may be operated for the purpose of filing, inspecting or removing papers, slips, bills or the like.

30 9 indicates a switch having leads 9^a, 9^a from one side thereof connected with a suitable source of electric supply, and leads 9^b, 9^b from the opposite side thereof connected with the motor 6.

35 9^c indicates the circuit closing arm of the switch 9.

10 indicates a plate secured by screws 10^a to the inside of one of the side walls 1^a of the casing 1.

40 10^b indicate a pair of guides secured to the plate 10 by screws or other devices 10^c.

10^d indicates a frame having its opposite ends slidably supported by the guides 10^b.

45 10^e indicates a link or rod rigidly connecting the frame 10^d and circuit closer 9^e together. The operation of the frame in one direction, for instance toward the rear of the casing 1, will close the circuit and set the motor 6 in operation; and moving the frame 10^d back to normal position will open the switch and stop the motor.

50 11 indicates a spring having one end connected to a pin or suitable stationary device 11^a supported by a plate 10 and its opposite end connected to the frame 10^d. This spring 11 tends to maintain the frame 10^d in a forward position, and the switch open, but permits it to slide rearwardly to move the switch closer 9^e.

60 10^f, 10^f, indicate stops carried by the frame 10^d at or near its opposite ends and extending forward to engage the rear face of the adjacent frame member 1^f to limit its forward movement.

65 10^g indicates a laterally extending plate

or flange provided on the plate 10^d and extending from end to end thereof. The purpose of this plate will be presently described.

11 indicates a frame supported at its opposite ends by blocks 11^a and provided along its opposite longitudinal edges with flanges 11^b. 70 11^c indicates a series of openings formed in each flange 11^b, each opening in one flange alining with an opening in the opposite flange.

12 indicates a series of keys one for each bill holding section or device 7. Each key is slidably mounted in two alined openings 11^c, in the flanges 11^b, the free ends of the keys extending into engagement with the flange or plate 10^d. The keys 12 also extend through suitable openings 12^a in the frame member 1^f. They are provided on their front ends with heads or buttons 12^b, which may carry a suitable index or signal character to indicate the bill holding section corresponding thereto.

75 12^c indicate compression springs, each surrounding a key 12 and interposed between its button 12^b and the frame 1^f. Each of the keys 12 is preferably formed with a shoulder or off-set 12^d which engages the rear flange 11^b of the frame 11 and limits its outward movement under the influence of the spring 12^c.

80 12^e indicates a series of notches one formed in one edge of each key 12. As shown in the drawings, the notch 12^e of each key 12 is arranged rearward of the notch 12^d in the key below it.

85 13 indicates a series of lock and release devices one for each key 12 and arranged in stepped order relative to each other corresponding to the arrangement of the notches 12^e. Each of these devices comprises a 90 bracket 13^a mounted on the frame 11 and provided with a pivot pin 13^b, a key engaging or lock and release member 13^c swingably mounted on the pin 13^b, and a spring 13^d preferably fixed to the frame 10 and bearing 95 against and normally pressing the said member outwardly. Each key engaging member 13^c preferably consists of a lever depending downwardly behind the adjacent key and a forwardly extending arm 13^e. The 100 frame 11 is formed with a series of stepped 105 openings 11^d through which the levers 13^c operate.

110 14 indicates a series of trip devices, one 110 for each bill holding device 7, projecting 115 laterally therefrom on that side adjacent the 120 keys 12.

125 The levers 13^c are held in rearward position against the springs 13^d by the keys 12; that is, when the keys are in their normal or forward position, the lower edges of the keys engage the levers 13^c and hold them back against the springs 13^d. In this position of the levers 13^c, the arms 13^e will be supported in a downwardly inclined po- 130

sition out of the path of the trip devices 14. If now it is desired to bring a particular bill holding section into operative position for manipulation, the following operations take place: The key 12 corresponding to that section is pressed inwardly. This operation slides the frame 10^a rearwardly which in turn closes the switch. The motor now operates and drives the chains 4. The inward 5 sliding of the key 12 moves the notch 12^a formed therein into register with the adjacent lock and release member 13^c. As soon as the notch 12^a and member 13^c register with each other, the latter, acting 10 under the influence of the spring 13^d, quickly swings into the notch 12^a, locks the key 12 against rearward movement (see Figs. 6 and 7) and moves the arm 13^e carried thereby upward into the path of the trip 14 carried 15 by the device 7 which is to be arrested at the operative position. As the inward and outward movement of each key 12 controls the forward and rearward movement of the frame 10^a, it will be understood 20 that the switch 9 will remain closed, and the motor continue to operate the chains 4, until the key, which has been operated, is released. When the trip 14 device of that 25 bill holding section corresponding to the key 12, which was operated, passes the key control mechanism, it strikes the arm 13^e, moves it downwardly and swings the lever 13^e rearwardly or out of the notch 12^a of the key. The latter, being released, returns to 30 normal position under the influence of the spring 12^c and permits the frame 10^a to return to its first position. The switch 9 being opened by the frame 10^a cuts off the current to the motor, which, together with the 35 driving mechanism immediately comes to a stop with the bill holding section in operative position. As each key 12 controls one of the bill holding devices, any one of them by the operation of its respective key, can 40 be brought around to and automatically arrested or stopped at the operative position. When any one of the keys 12 is pressed inwardly, the switch 9 is closed and throws in 45 the motor. It follows from this that the moving mechanism can be started from any 50 position and will continue to operate until the section corresponding to the operated key comes around into a position whereby its trip device releases the key and opens 55 the switch. The moving mechanism then comes to a stop with the said section in register with the opening in the case and in the proper operative position.

Each trip device 14 preferably comprises 60 an arm 14^a pivotally mounted in a block 14^b whereby it may be moved out of operative position (see dotted lines in Fig. 8), when the adjacent bill holding section is not in use.

65 14^a indicates a spring which bears against

the rear end and one face of the arm 14^a and holds it in either an operative or inoperative position.

Means may be provided for adjusting each trip device 14 up and down on the adjacent frame 7^a of its bill holding section in order to throw the switch 9 at such a point in the downward movement of the bill holding section that the latter will come to a stop in the correct position; that is, in case 70 the bill holding section does not stop in the operative position upon the opening of the switch 9, the trip device can be adjusted to release the key 12 at an earlier or later point in its downward movement as the case may be. Of these means, 15 indicates an elongated slot formed in one side of each frame or case 7^a and 15^a indicate screws which extend through each slot and fit screw threaded openings 14^a in the adjacent block 14^b, 75 the heads of the screws bearing against the inner faces of the adjacent case 7^a. By loosening the screws 15^a each block 14^b may be adjusted along the slot 15 either up or down. 80

To those skilled in the art of making filing appliances of the class described, many alterations in construction and widely differing embodiments and applications of my invention will suggest themselves, without departing from the spirit and scope thereof. 85 My disclosures and the description herein are purely illustrative, and are not intended to be in any sense limiting. 90

What I claim is:—

1. In a filing appliance, the combination of a support, a series of filing sections, a mechanism for supporting and moving said filing sections through an endless path, a motor for driving said mechanism, a series 100 of keys, a normally open switch common to said keys and operated thereby for controlling said motor, and a spring actuated device normally arranged in the path of movement of one of said filing sections and arranged to be operated thereby to stop the section at a prearranged position, each of said devices being held in in-operative position by an adjacent key, but being released thereby when said key is operated. 105

2. In a filing appliance, the combination of a support, a series of filing sections, mechanism for moving said filing sections on the support through an endless path, a motor for driving said endless mechanism, a release device arranged to be actuated by each of said filing sections, a spring arranged to normally hold said device in the path of movement of a filing section, a key for each of said release devices arranged to hold it out of operative position, but permitting it to move into operative position when the key is operated, each of said keys being formed with a shoulder arranged to be engaged by the adjacent release device to lock the key in 110 115 120 125 130

- 1 operated position, and a switch common to and operated by said keys for controlling the operation of the motor to stop each filing section at a predetermined position.
- 5 3. In a filing appliance, a series of filing sections each comprising a plurality of holders arranged to swing relative to each other, mechanism for supporting and moving said sections through an endless path, a motor for operating said mechanism, a series of keys, one for each of said sections, for controlling the starting and stopping of said mechanism, a switch common to said keys and arranged to be closed thereby, a series of spring actuated release devices one for each of said filing sections and normally arranged in the path thereof, each key operating to hold an adjacent release device in in-operative position but permitting it 10 to move into operative position when the key is operated to close the switch, and a stop or shoulder on each key arranged to be engaged by the adjacent release device for holding the key in operated position until 15 the release device is engaged by its corresponding filing section.
4. In a filing appliance, a series of filing sections each comprising a plurality of holders arranged to swing relative to each other, mechanism for supporting and moving said sections through an endless path, a motor for operating said mechanism, a series of keys, one for each of said sections, for controlling the starting and stopping of 20 said mechanism, a switch common to said keys and arranged to be closed thereby, a series of spring actuated release devices one for each of said filing sections and normally arranged in the path thereof, each 25 key operating to hold an adjacent release device in in-operative position when the key is operated to close the switch, a stop or shoulder on each key arranged to be engaged by the adjacent release device for holding the key in operated position until 30 the release device is engaged by its corresponding filing section.
- 35 5. In a filing appliance, a series of filing sections each comprising a plurality of holders arranged to swing relative to each other, mechanism for supporting and moving said sections through an endless path, a motor for operating said mechanism, a series of keys, one for each of said sections, for controlling the starting and stopping of 40 said mechanism, a switch common to said keys and arranged to be closed thereby, a series of spring actuated release devices one for each of said filing sections and normally arranged in the path thereof, each 45 key operating to hold an adjacent release device in in-operative position when the key is operated to close the switch, a stop or shoulder on each key arranged to be engaged by the adjacent release device for holding the key in operated position until 50 the release device is engaged by its corresponding filing section, and means for returning the key to normal position when the release device is operated.
- 55 6. In a filing appliance, a series of filing sections each comprising a plurality of holders arranged to swing relative to each other, mechanism for supporting and moving said sections through an endless path, a motor for operating said mechanism, a series of keys, one for each of said sections, for controlling the starting and stopping of 60 said mechanism, whereby each of said filing sections can be brought to a predetermined position of rest, a normally open switch common to said keys and arranged to be closed thereby, a pair of co-operating elements for each filing section for controlling the opening of the switch, one element of a 65 pair being carried by each filing section and

the other element of a pair being swingably supported adjacent to one of said keys, each of the last mentioned elements being normally arranged in the path of movement of its co-operating element carried by a filing section and arranged to lock the adjacent key in operated position to close the switch, but operating when engaged by its co-operating element to release the key and permit the opening of the switch.

7. In an apparatus of the character described, the combination of a leaf or frame holding section, mechanism for supporting and moving said section to and from an operative position, a motor for driving or moving the said mechanism, a key and switch mechanism operated thereby for controlling the motor, a shoulder on said key, a swingable lock and release device engaging said shoulder for locking the key in operated position and releasing it therefrom, and a trip carried by the said section for swinging the lock and release device to release the key.

8. The combination of a series of frame holding sections, mechanism for supporting and moving said sections to and from a predetermined position, a motor for operating said mechanism, a series of keys, one for each of said sections, for controlling the starting and stopping of said mechanism, whereby each section can be arrested at the predetermined position, a normally open switch common to said keys and arranged to be closed thereby, a pair of co-operating elements for each section arranged to control the operation of one of said keys, one element of a pair being carried by a frame holding section and the other element of a pair being swingably supported adjacent to one of said keys, each of said last mentioned elements being normally arranged in the path of its co-operating element carried by the frame holding section and arranged to lock the adjacent key in operated position, but operating when engaged by its co-operating element to release the key and permit the opening of the switch, the elements of the pairs of co-operating elements carried by the frame holding sections being movable to an inoperative position.

9. In a filing appliance, the combination of a casing provided with an opening, a series of filing devices, endless mechanism for supporting and moving said filing devices relative to said opening, a motor in gear with said endless mechanism for moving it, a switch, connections between said motor and switch, a sliding frame for opening and closing said switch, a spring for normally maintaining said switch open, a series of keys one for each filing device, and each arranged to engage said sliding frame to close the said switch when operated, a spring operated lock for each key arranged

to lock the key in operated position and operating through the key and said sliding frame to maintain the switch in closed position, the said lock being held out of locking relation with the adjacent key when the latter is in inoperative position but being released by the movement of the key to close the switch and a device carried by each filing device and coöperating with one 10 of the said locks to release it after it has locked the adjacent key.

9. In a filing appliance, the combination of a casing provided with an opening, a series of filing devices, endless mechanism 15 for supporting and moving said filing devices relative to said opening, a motor in gear with said endless mechanism for moving it, a switch, connections between said motor and switch, a spring for normally 20 maintaining said switch open, a series of keys one for each filing device and each adapted to close the said switch when operated, a spring operated lock for each key provided with an extension, and arranged 25 to lock the adjacent key after it is operated to close the switch, each lock being held out of locking position by the adjacent key when it is in normal position but being released by the movement of the key to close 30 the switch, and devices, one carried by each filing device, the said devices being off-set relative to each other, and the said extensions of the locks being off-set relative to each other and each arranged in the path of 35 one of said devices, whereby the adjacent lock is automatically released by the latter.

10. In a filing appliance, the combination of a casing, a series of filing devices, each arranged to be stopped at a predetermined 40 position, endless mechanism for supporting and moving said filing devices, an electric

motor in gear with said endless mechanism for moving it, a switch, connections between said motor and switch, a sliding frame for opening and closing said switch, a spring 45 for normally maintaining said switch open, a series of keys one for each filing device and each adapted to operate said frame, a spring operated lock for each key provided with an extension and arranged to engage 50 the adjacent key for locking it in actuated position, the said lock being held in inoperative position by the adjacent key but being released by the movement of the key to close the switch, devices, one carried by each filing device, the said devices being off-set relative to each other, and the said extensions of the locks being off-set relative to each other and each arranged in the path of one of said devices and arranged to be engaged thereby, whereby the adjacent lock is automatically released by the latter, and means for returning each key to normal position after the release of the adjacent lock. 55

11. In an apparatus of the character described, the combination of a leaf or frame holding section, mechanism for supporting and moving the said section to and from an operative position, a motor for driving or moving the said mechanism, a key and mechanism operated thereby for controlling the motor, an automatically operating device for locking the key, including an extended arm, and a trip device engaging said arm for releasing the lock device. 60

In testimony whereof I affix my signature, in the presence of two witnesses.

HARRY J. HICK.
